UNITED STATES PATENT OFFICE.

WALTER L. ACKERMAN, OF HOLLYWOOD, CALIFORNIA, ASSIGNOR OF ONE-HALF TO
YALE CORPORATION, OF LOS ANGELES, CALIFORNIA, A CORPORATION OF CALI-
FORNIA.

METHOD OF PRODUCING STAGE EFFECTS.

Application filed June 13, 1921. Serial No. 477,132.

To all whom it may concern:

Be it known that I, WALTER L. ACKERMAN, a citizen of the United States, and a resident of Hollywood, Los Angeles, in the county of Los Angeles and State of California, have invented certain new and useful Improvements in Methods of Producing Stage Effects, of which the following is a specification.

10 This invention relates to methods of producing stage effects, and more especially to the production of an illusory effect.

An object of the invention is to provide two different appearances with the same object or objects, according as said object or objects are illuminated from the front or the background therefor is illuminated from a position between the object and the background.

20 Another object is to so illuminate an object or objects, while making motion pictures thereof, that the object or objects will be seen in silhouette at one time and in full illumination at another time and the change 25 from silhouette to full illumination gradually effected so as to give the appearance to the spectator of a gradual transition of a certain object or objects into an entirely different object.

30 The accompanying drawings illustrate an apparatus by which the method may be performed.

Figure 1 is a front elevation of a set as it appears illuminated only from the rear 35 so as to silhouette the upper outline of the various objects upon the illuminated background.

Figure 2 is a view similar to Figure 1 showing the set as it appears when illuminated only from the front.

40 Figure 3 is a broken sectional elevation on the line indicated by x^3-x^3 , Figure 2.

Figure 4 is a plan view of Figure 2, with the stage walls in section.

45 Figures 5 and 6 are sectional elevations of two different objects, respectively, in Figures 1 to 4, inclusive.

In the instance shown in the drawings, a stage is represented at 1 and the interior of 50 the stage is provided with a set comprising various objects: for example, a piano 2, an ottoman 3, a table 4, an ash tray 5 on the table, a piano lamp 6, chairs 7, 8, a settle 9 and a bookcase 10. It is understood that 55 the objects just enumerated may be real or

imitation, and also that the entire set may be nothing more than a picture, the upper outline of which corresponds to the outline of the upper portions of various objects in the picture. It is understood that one or 60 more objects may be used, depending upon the results to be produced. The objects shown, in this instance, are inanimate, but it is understood that one or more of them may be animate, for example, a living person or persons.

It is essential, where actual objects, such, for example, as chairs and tables, are employed, that a certain part or parts thereof be blanked out as indicated at 11 for the 70 table 4, at 12 for the chair 8 and at 13 for the settle 9, so as to prevent light from passing from the rear beneath the table top and beneath the seats of the chair 8 and settle 9.

The stage 1 is provided with a rear wall 75 or background 14 which extends above the level of the objects in the set so that portions of the outline of said objects can be seen against the background 14. Between the various objects and the background 14 80 are arranged sources of light 15 which may be electric lamps, as shown, and the lamps are regulated by means well known in the art of stage lighting for gradually increasing and decreasing the intensity of the 85 illumination of the background. In front of the various objects, at the foreground of the stage, are arranged sources of light 16 which are also electric lamps controlled so that the illumination from the front may 90 be gradually increased or decreased in intensity. In the stage 1 is indicated a motion picture camera 17.

The method is performed with the above described apparatus as follows: Full illumination of the background from the rear of the set is effected by the light sources 15 so as to produce the silhouette effect shown in Figure 1 of the drawings. In this silhouette can be seen the upper portion of 100 the outline of the chair 12, settle 13, table 4, ash tray 5, smoke 18 arising from the ash tray, bookcase 10, books 19 on the bookcase, and the lamp 6. These partial outlines as thus seen in silhouette against the background 14, in this particular instance, merge 105 and give the appearance of a portion of the skyline of a city, the ash tray 5 giving the appearance of a chimney and the smoke 18 arising from the ash tray appearing to be 110

smoke discharging from the chimney. In this instance, the settle 9 is provided with openings 20 which in the silhouette effect of Figure 1 appear as illuminated windows.

5 The bookcase 10, in this instance, is provided with vertical slots 21 which are adapted to register on the motion picture film with the fringe 22 of the lamp to give the appearance of windows in the silhouette. The light 10 from the sources 15 passes through the openings 20 and also through the slots 21.

The illumination of the background being effected as above described, with the lights 16 preferably extinguished, the camera 17 15 will be operated in the usual manner to produce a series of exposures on the motion picture film so as to produce a series of negatives showing the silhouette as in Figure 1. While the camera is being operated, 20 the illumination of the background will be diminished in intensity and illumination will be effected in front of the objects by the light sources 16. These sources 16 will preferably be operated to gradually increase 25 the intensity of the illumination at the same time that the intensity of the background illumination is being diminished, so that the silhouette effect gradually disappears and the actual objects or their representations or 30 images come more clearly into view under the strengthening illumination from the front. After the illumination from the front has reached a greater degree of intensity than that of the background, the de- 35 tails of the objects will be registered clearly enough on the negative film to produce, when the picture is subsequently projected on the theater screen, the appearance of said objects as seen in Figure 2. The different appearances of the set during the 40 time of gradual transition of the illumination from the rear of the objects to the front thereof are not illustrated in the drawings, but only the appearances as at 45 full rear illumination and full front illumination.

The "frames" thus produced by operation of the camera can be used with good effect for the opening portion of a motion picture, 50 act, or scene, either with or without a title or sub-title, and it is clear that by reversing the operation hereinbefore described so as to gradually decrease the front illumination and gradually increase the background il- 55 lumination, while operating the camera, an act or scene may be ended by reversal of the appearance of the set. That is to say, the details of the objects as seen in Figure 2 will be caused to gradually disappear and 60 only portions of the outline thereof remain to form the silhouette shown in Figure 1.

The set hereinbefore described is merely typical of the various effects that may be produced by this new method, and it will 65 be understood that the description of the

method in conjunction with the particular set illustrated is only for the purpose of making clear how the various steps of the method are performed.

As an example of animate objects which 70 may be employed to good advantage in performing the method, a camel may be selected, the background being illuminated and the camel being unilluminated for a time so that the hump of the camel will appear in 75 silhouette as a distant mountain. When the illumination from the front overbalances the rear illumination, the camel will no longer appear as a mountain but in its true character. 80

It will be clear from the foregoing that in this method an object is illuminated from a position in front thereof, and the background for said object from a position between the object and the background, and 85 that there is effected a gradual change in the point of illumination of the object by gradually increasing the intensity of one illumination and decreasing the intensity of the other illumination while the camera is being operated to make a series of exposures, 90 whereby there is produced a series of "frames" which, when projected on the exhibiting screen, will give the illusory effect of the transition of a silhouette of a familiar object or objects into other familiar objects of an entirely different character or, vice versa, the transition of familiar objects into a silhouette of a different familiar object or objects. 95

It is to be understood that, in this specification, the term "object" defines either an object or its image, that is to say, the actuality, a mere imitation or a photograph or other picture of the actual object or imitation. 100

It is readily seen that the invention is also useful on the "legitimate" stage, so-called, and that when so used the audience will view the set itself and not motion pictures thereof, in which event the operation of making exposures on a film will be dispensed with. 110

I claim:

1. In the method of making motion pictures, the combination of steps consisting in illuminating an object from the rear with gradually decreasing intensity, at the same time illuminating the object from the front with gradually increasing intensity, and making a series of exposures of the object while the change in illumination is being effected. 115

2. In the method of making motion pictures, the combination of steps consisting in illuminating an object from a position in front thereof and a background from a position between the object and the background, and gradually increasing the intensity of one illumination and decreasing the intensity of the other illumination. 125

3. In the method of producing stage effects, the combination of steps consisting in illuminating mainly from the rear an object whose silhouette corresponds to that of another object of an entirely different appearance when illuminated from the front, illuminating said first object from the front with gradually increasing intensity to disclose its true character, and making a series of motion picture negative exposures of the object while the change in illumination is being effected. 20
- 5 4. In the method of producing stage effects, the combination of steps consisting in illuminating mainly from the rear a three dimensional object whose silhouette corresponds to that of another three dimensional object of an entirely different appearance 25
- 10
- 15
- 10
- 15
- when illuminated from the front, and illuminating said first object from the front to disclose it in its three dimensions. 20
- 5 5. In the method of producing stage effects, the combination of steps consisting in illuminating mainly from the rear an object whose silhouette corresponds to that of another object of an entirely different appearance when illuminated from the front, and illuminating said first object from the front with gradually increasing intensity to disclose its true character. 30

Signed at Los Angeles, California, this 28th day of May, 1921.

WALTER L. ACKERMAN.
